US00D730362S

(12) **United States Design Patent**
Akana et al.

(10) **Patent No.:** **US D730,362 S**
(45) **Date of Patent:** **** May 26, 2015**

(54) **COVER**

(71) Applicant: **Apple Inc.**, Cupertino, CA (US)

(72) Inventors: **Jody Akana**, San Francisco, CA (US); **Bartley K. Andre**, Palo Alto, CA (US); **Jeremy Bataillou**, San Francisco, CA (US); **Daniel J. Coster**, San Francisco, CA (US); **Danielle De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zörkendorfer**, San Francisco, CA (US)

(73) Assignee: **Apple Inc.**, Cupertino, CA (US)

(**) Term: **14 Years**

(21) Appl. No.: **29/479,056**

(22) Filed: **Jan. 10, 2014**

Related U.S. Application Data

(63) Continuation of application No. 29/455,191, filed on May 17, 2013, now Pat. No. Des. 697,512, which is a continuation of application No. 29/425,618, filed on Jun. 25, 2012, now Pat. No. Des. 682,836, and a continuation of application No. 29/432,296, filed on Sep. 14, 2012, now Pat. No. Des. 682,838, said application No. 29/425,618 is a continuation of application No. 29/384,903, filed on Feb. 4, 2011, now Pat. No. Des. 663,304, which is a continuation-in-part of application No. 29/375,197, filed on Sep. 17, 2010, now Pat. No. Des. 658,186, said application No.

29/432,296 is a continuation of application No. 29/418,778, filed on Apr. 20, 2012, now Pat. No. Des. 671,948, which is a continuation of application No. 29/375,197, filed on Jun. 17, 2010, now Pat. No. Des. 658,186.
